UNITED STATES PATENT OFFICE.

JOSEPH FORSTER, OF VIENNA, AUSTRIA-HUNGARY.

UMBRELLA OR PARASOL SUPPORT.

SPECIFICATION forming part of Letters Patent No. 256,308, dated April 11, 1882.

Application filed January 3, 1882. (No model.) Patented in Austria July 30, 1879, and April 12, 1880, in Hungary July 30, 1879, and April 12, 1880, in England June 11, 1880, in France August 25, 1880, in Belgium October 15, 1880, in Italy October 16, 1880, and in Germany May 18, 1881.

To all whom it may concern:

Be it known that I, JOSEPH FORSTER, engineer, a citizen of Austria, residing at Vienna, in the Crownland of Nether-Austria and State of Austria-Hungary, have invented certain new and useful Improvements in Umbrellas and Parasols, (Sunshades;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The umbrellas and parasols made heretofore have been so constructed that the inclined rib-braces prevent the top or center of the umbrella from being held near the head, and as this requires the umbrella to be held very high it does not afford as much protection as it would if it could be held lower.

The object of my invention is to avoid the above defects.

The invention consists in an umbrella or parasol provided with a support formed of four rods pivoted to each other at the ends, the upper ends of the upper rods being pivoted to the middle of the umbrella-top frame and the lower ends of the lower rods being pivoted to each other at the handle end of the umbrella-support, these several rods being provided with braces and binding-rods and locking-springs, as will be fully described hereinafter.

Reference is to be had to the accompanying drawings, forming part of this specification, in which similar letters of reference indicate corresponding parts in all the figures.

Figure 1 is a cross-sectional elevation of my improved umbrella or parasol, showing it raised or opened. Fig. 2 is a longitudinal side elevation of the upper parts of the pivoted rods, showing them folded. Fig. 2^a is a longitudinal side elevation of the same in a similar position, parts being in section. Fig. 2^b is a section on line *xx* of Fig. 2^a. Fig. 3 is a longitudinal front and side elevation of the middle joint-plate at the middle of the umbrella-top frame. Fig. 4 is a longitudinal elevation of one of the side joint-plates at the top of the

umbrella. Fig. 5 is a longitudinal front elevation of the lever for locking the umbrella in position when opened. Fig. 6 is a longitudinal elevation of one of the joint-plates for uniting the upper and lower rods. Fig. 7 is a longitudinal elevation of one of the slotted sleeves sliding on the lower rods for locking the rib-bracing rods in position when the umbrella is opened. Fig. 8 is a longitudinal elevation of the same and two of the rib-bracing rods pivoted to the same. Fig. 9 is a plan view of the top of the umbrella, showing it opened or raised.

The four rods A B C D are pivoted to each other at the ends and carry the umbrella-top A'. The upper rods, C and D, are beveled at their upper ends, as shown in Fig. 2, and are provided with recesses, into which a metal plate, *a*, of the shape shown in Fig. 3, passes. Parallel with each surface of the plate *a* a metal plate, *b*, is placed, these plates being removed in Fig. 2. The upper ends of the rods C D are pivoted to these metal plates *a* and *b* by pintles 1 and 2 passed transversely through the plates *a* and *b* and through the upper ends of the rods C D. The check-stud 3 prevents the rods C D from being spread too far and the lug *a'* prevents them from being brought together closer than necessary. The upper narrower part, *a*², of the plate *a* serves to receive the crown-plate *c* and the umbrella-point *c'*. The crown-plate *c* is of the usual construction, and is provided with the usual devices for holding the ribs *n*, and the cap *c'*, soldered to the crown-plate, is placed over the upper narrower part, *a*², of the plate *a*. Then the umbrella-point *c'* is inserted in the cap *c'*, and the several parts are united by means of the pintle 4.

For the purpose of holding the rods A, B, C, and D in the proper position when the umbrella is raised the rods C D are united by brace-rods E, having one end pivoted to the rod D by means of the pintle 5 and the other end pivoted by pintle 6 to the lugs *d* of the sliding sleeve *e* on the rod C, as shown in Figs. 1, 2, and 2^a.

Between the lugs or jaws *d* a latch-lever, *f*, provided with a transverse socket, *g*, is loosely mounted on the pintle 6. The upper end of

this lever is provided with a slot, *h*, into which a lug or stud, *h'*, of the rod *C* passes when the umbrella-top is raised.

One end of the lever *f* is provided with a spring, *h*², by the action of which the upper slotted end of the lever *f* is pressed against the rod *C*, so that when the sleeve *e* slides up the rod *C* the lug or stud *h'* of this rod *C* will snap into the slot *h* of the lever *f*, whereby the rods *E* will be locked in position and will hold the rods *C* and *D* separated. The rods *A* and *B*, to the upper ends of which the rods *C* and *D* are pivoted, are united at their lower ends by a hinge, *i*, and at their upper ends they are provided with hinge-plates *j*, held on these rods

A and *B* by rivets or tacks 7 and 8, and on the lower ends of the rods *C* and *D* by a pintle, 9, whereby hinged joints are formed. The meeting ends of the rods *A*, *B*, *C*, and *D* are cut out or recessed, so as to overlap each other, the inner parts of the upper rods, *C* and *D*, and the outer parts of the lower rods, *A* and *B*, being cut away, as shown in Fig. 2. In view of the construction and combination of the rods *A*, *B*, *C*, and *D*, described above, these rods can be swung or turned on their pintles 12 9 9 and brought into the position shown in Fig. 1, showing the umbrella or parasol opened; but when the umbrella or parasol is closed the rods fold closely against each other, as shown in Fig. 2, and prevent bending (or further folding) at the joints.

The rods *A*, *B*, *C*, and *D* can be provided at all the joints or hinges with protection-rings, as shown in Fig. 2, to prevent a rapid wearing off of these rods at the joints. Below the joints connecting the rods *A* and *C* and *B* and *D* springs *k* are provided for the purpose of holding the sleeves *l* in position when the umbrella or

40 parasol is opened.

The sleeves *l*, Figs. 1, 7, and 8, are provided at their upper ends with lugs or jaws *l'*, to which the brace-rods *m* are pivoted by means of wire pintles. These brace-rods are pivoted to the ribs *n* in the ordinary manner, as shown in Figs. 1 and 9.

If the umbrella or parasol is opened the springs *k* snap into the slots *o* of the sleeves *l* and rest against the rings at the upper ends 50 of these sleeves, as shown in Fig. 1. The handle of the umbrella or parasol support consists of two parts, *p* *p'*, united by the joint *i*, (which thus pivots the rods *A* and *B* to each other,) and if desired the handle parts and the rods 55 *A* and *B* can be made integral, or the handle parts can be screwed on or otherwise attached to the lower ends of these rods.

The handle part *p* is provided with a button-stud, *q*, to which an elastic band, *r*, is attached, 60 which serves to hold the parts of the umbrella or parasol together when the same is closed.

The pivoted rods *A* and *C* and *B* and *D* form two rods provided with a joint at or above the middle, permitting of folding of the rods, which 65 are pivoted to each other at the top and bottom, parallel with each other when the um-

rella or parasol is closed. If the umbrella or parasol is opened the rods bend outward at their joints and form an irregular lozenge or quadrangle, into which the head and hat of the person carrying the umbrella or parasol can pass, permitting the middle of the umbrella-top to be held directly above the head or hat, whereby the front and rear sides of the body will be protected equally from rain or the sun's rays.

Having thus fully described my invention, I claim as new and desire to secure by Letters Patent—

1. An umbrella or parasol constructed, substantially as herein shown and described, with a support formed of a series of rods pivoted to each other and constituting a frame which forms two parallel rods when the umbrella is closed, and an irregular quadrangle or lozenge when the umbrella is opened, whereby the head and hat of the person carrying the umbrella or parasol can be placed within the quadrangle, so as to be directly under the middle of the umbrella-top, as set forth.

2. The combination, with an umbrella-top, of a support formed of two rods provided with hinges between their ends, these rods being pivoted to each other at the lower or handle ends and at their upper ends at the middle of the umbrella-top frame, substantially as herein shown and described, and for the purpose set forth.

3. The combination, with the umbrella-top *A'*, of the rods *A*, *B*, *C*, and *D*, forming the folding support for the umbrella-frame, of which rods *C* and *D* are pivoted to each other at the middle of the umbrella-top frame, the upper end of the rod *A* being pivoted to the lower end of the rod *C*, the upper end of the rod *B* to the lower end of the rod *D*, and the lower ends of the rods *A* and *B* pivoted to each other, substantially as herein shown and described, and for the purpose set forth.

4. The combination, with the umbrella-top *A'*, of the rods *A*, *B*, *C*, and *D*, pivoted to each other in the manner described, and of the brace-bars *E*, pivoted to one of the upper rods, *C* or *D*, and to a sleeve, *e*, sliding in the other upper rod, *C* or *D*, substantially as herein shown and described, and for the purpose set forth.

5. The combination, with the umbrella-top *A'*, of the rods *A*, *B*, *C*, and *D*, pivoted to each other in the manner described, of the pivoted brace-bars *E*, the sliding sleeve *e*, and a locking device attached to this sleeve, substantially as herein shown and described, and for the purpose set forth.

6. The combination, with the umbrella-top *A'*, of the rods *A*, *B*, *C*, and *D*, pivoted to each other in the manner described, of the brace-bars *E*, the sliding sleeve *e*, to which one end of the bars *E* is pivoted, the stud or catch *h'*, projecting from that upper rod, *C* or *D*, on which the sleeve *e* slides, and the latch *f* on the sleeve *e*, substantially as herein shown and described, and for the purpose set forth.

7. The combination, with the umbrella-top A', of the rods A, B, C, and D, pivoted to each other, as described, the umbrella-point c², and the brace-bars E, and devices for locking these 5 brace-bars, substantially as herein shown and described, and for the purpose set forth.

8. The combination, with the umbrella-top A', of the rods A, B, C, and D, pivoted to each other, as described, umbrella-point c², the plates 10 a and b, the brace-bars E, and devices for locking these brace-bars, substantially as herein shown and described, and for the purpose set forth.

9. The combination, with the umbrella-top 15 A', of the rods A, B, C, and D, pivoted to each other, as described, the umbrella-point c², the crown-plate c, to which the ribs n are pivoted, the cap c', the brace-bars E, and of devices for locking these brace-bars, substantially as herein 20 shown and described, and for the purpose set forth.

10. The combination, with the umbrella-top A', of the rods A, B, C, and D, pivoted to each

other in the manner described, of the sleeves l l, adapted to slide on the lower rods, A and B, 25 the brace-rods m, pivoted to these sleeves and to the ribs n, and of devices for locking those sleeves l l in position, substantially as herein shown and described, and for the purpose set forth.

11. The combination, with the umbrella-top A', of the rods A, B, C, and D, pivoted to each other, as described, the sleeves l l, provided 30 with slots o, and adapted to slide on the lower rods, A and B, the brace-rods m m, pivoted to these sleeves l l and to the ribs n, and the locking-springs k k on the rods A and B, for locking the sleeves l l in position, substantially as herein shown and described, and for the purpose set forth.

In testimony whereof I affix my signature in presence of two witnesses.

JOSEPH FORSTER.
